Veneering Mach.

No 17,958.

Patented Aug. 11, 1857.

Inventor
Gilbert Bishop

UNITED STATES PATENT OFFICE.

GILBERT BISHOP, OF NEW YORK, N. Y.

ROTARY VENEER-MACHINE.

Specification of Letters Patent No. 17,958, dated August 11, 1857.

To all whom it may concern:

Be it known that I, GILBERT BISHOP, of the city of New York, N. Y., mechanical engineer, have invented a new and useful 5 Machine for Cutting Veneers and other Thin Stuff from the Log, and that the following is a full and exact description thereof, reference being had to the accompanying drawings, and the letters of reference thereon, 10 making part of this my specification.

Figure I, represents a plan of the machine or top view, a part of the circular disk plate being removed in the drawing to show the parts of the mechanism beneath it. Fig. II, 15 represents a back view or elevation of the machine. Fig. III, represents a front view or elevation.

In all the figures like letters represent like parts.

20 The nature of my invention consists in cutting veneers and other thin stuff by a knife with a circular or curved edge in rotation in the line of its edge, while the log from which the veneer is to be cut is vibrated or turned toward the knife edge as it passes, so that the knife progressively covers the whole top surface of the log and cuts the veneer by a continuous rotary drawing, thrusting and varying stroke of 25 30 the edge from point to heel, as the log is presented to and brought in contact with it.

The frame and floor of the machine consist of a bed plate A, A, and the two parallel upright standards B, B, connected by 35 a cross head C, all of which should be of iron firmly put together and of sufficient strength to sustain the action of the machine without yielding. The bed plate should be well supported upon masonry, or 40 compact ballasting underneath, and should have a very accurate level.

The knife for cutting the veneer is placed upon the under surface of a disk or solid wheel of metal D, D, fixed upon a vertical 45 shaft D', having its lower bearing in a block D'', where it is received and revolves in a socket joint turned to fit it. The upper bearing of D', is the cross-head C, through which it passes, and which is provided with a proper journal box or bush in which it revolves. The disk D must be a plate of sufficient thickness to carry the knife steadily through the log, and the under surface should be regular and even and 50 perfectly horizontal; the upper surface may taper so as to grow thinner from the cen-

ter toward the edge. Through this disk is cut the eccentric slot E, which is for the purpose of forming a mouth (as in a plane stock) or opening for the veneer to come 60 through as it is cut by the knife. The side of the slot toward the center of the disk is beveled away from its lower edge as indicated by the line e, e, Fig. I, and the mouth is also beveled and wider at the end where 65 the cut begins than at the opposite end toward which it tapers evenly. Upon the under side of the disk is fixed the knife, the edge of which forms a continuation of the beveled side of the slot just described, and 70 has the same bevel to form the edge. This knife is a flat plate of steel having its cutting edge curved to conform to the slot or mouth as described; its two ends are parallel and straight and the back is straight. 75 It is inserted into a recess in the under surface of the disk, made to fit it, and so that its under surface will just be flush and even with the rest of the under surface of the disk, but project according to the thickness 80 of the veneer to be cut. It is fastened to the disk by means of screws passing through it and into the disk from the under side; the heads of these screws must not project below the under surface of the knife. Upon 85 the upper side of the disk and over the knife plate are placed the adjusting screws f, f, f, f, the ends of which screws pass through the disk and touch the upper surface of the knife plate. These screws by 90 being turned in connection with the fastening screws in the knife plate underneath, serve to adjust the knife plate, and hold it firmly when fixed, in the desired position.

The log from which the veneer is to be 95 cut is placed in an oblong rectangular framed box or chest in front of the machine and under the rotary disk, as shown at G, G, G, G. This box is supported at the center or middle by a vertical shaft H, Fig. 100 I, to which it is fixed, and upon the head of which it rests. A shoulder or collar piece H', Fig. III, is fastened to the under side of the box around the head of the shaft to insure greater steadiness and strength; a 105 circular pedestal or block H', receives the lower end of shaft H, and its top surface being smooth and flat forms a support for the shoulder H', and upon which it vibrates, and serves to keep the log box above, true 110 and steady. As a further support to the log box there are placed under either end of

the box two circular ways, the top edges of which are seen at I, I, Fig. I; they rest upon and are fastened to the bed plate by the flanges and screws I, i. The circular ways, 5 I, I, extend as far as the line of vibration of the box G. The under surface of box G traverses upon and is sustained by the upper edges of the circular ways. The upper surface or edge of box G, is arranged to just 10 pass freely under the disk D, close to it but without touching it, and so that the knife edge will pass over the whole upper surface of the log as the knife rotates with the disk. 15 For the purpose of vibrating or turning the box and log held by it so as to meet the edge of the knife and produce the compound drawing and thrusting stroke desired, I connect and combine the revolution of shaft D' with the log box in the manner 20 and by the means now to be described. Upon the end of box G, is fixed the bracket g, having upon it the pin 1. In the rear of the log box in line with shaft D' and upright B is placed the vertical shaft K, having 25 its lower bearing in block k and its upper bearing in the projecting bracket L fastened to standard B (Fig. II). Upon shaft K is placed the straight arm K', adjustable upon the shaft and held by screw a passing 30 through it to the shaft. The arm K' is made adjustable in order to increase or reduce the play of the box G with which it is connected as hereafter described. Upon the projecting end of arm K' is the vertical pin 35 2. The bar M connects K' with bracket g, and is held by the pins 1 and 2 passing through holes in either end; so that when shaft K is turned the box G must move with it. Shaft K is made to turn by means 40 of the curved toe or cam L''' fastened upon it by screw b, and adjustable, and which is operated by the cam piece N fixed upon shaft D adjustable upon the shaft by screws c, c, passing through slots d, d, into 45 the ring piece or collar O fast to the shaft D'. Upon the under side of the ring piece or collar O is another cam P fastened to it by screws and slots so as to be adjustable, and at an angle to cam N greater or less according to the play to be given to the log 50 box. Upon the box G at the end opposite to g, is the bracket g'. In the seat and in line with the shafts D' and K is the vertical shaft K'' having its lower bearing in block k' and its upper bearing in bracket L' fast to upright B. Upon K'' is the 55 horizontal arm Q adjustable and fixed by screw a'. The loose end of arm Q is connected with bracket g' on the log box by means of the connecting bar M' having at 60 either end holes to fit on to the upright pins 3 and 4 and turn freely upon them. Upon shaft K'' below Q is fixed the curved cam or toe L'' adjustable and secured to shaft 65 by screw b'.

K'' is turned by cam P pressing against the toe L by the revolution of shaft D' and by this arrangement the end of the box at g' is thrown back to meet the approaching edge of the knife, as it is carried forward 70 by the rotation of shaft D' and disk D.

The box G for holding the log is open at the sides with a space in front sufficient to admit the log; it is provided with a movable or false bottom. This bottom is composed of three pieces 5, 6, 7, two of which 5 and 7 run the whole length of the inside of the box; the third or middle piece 6 is a caul or flat plate pierced with holes, to admit of short screws by which the log is 80 fastened to the plate or caul. The two pieces 5 and 7 have their inner edges beveled underneath, and the middle plate has its edges beveled from above so that it slides or shuts under the beveled edges of the side 85 pieces and is so held down, but being shorter than the two pieces 5 and 7 it will slide toward either end of the box as may be required for adjusting the log to the knife edge. 90

For placing or removing the caul (6) with or without the log attached, the bottom piece 7 is made to act as a clamp in connection with 5 by the operation of screws 8, 9, 10 passing through the fixed brackets 12, 13, 14 fast to longitudinal plate 15 at its front edge, and into corresponding bracket underneath plate 7 and fastened to it, plate 7 being kept in a true line by pins on its under side sliding in corresponding straight slots in the plate underneath. When screws 8, 9, 10 are screwed up they close the clamp plate 7 upon the caul, 6, and it is thus in connection with 5 held in place; and when the screws are unscrewed they withdraw clamp 105 plate 7, and release the caul, 6, to be taken out. 100

For effecting and adjusting the feed of the log to the knife there are fixed to the lower part of the log box G two pair of horizontal pulleys, front and rear of the same size and in the same line or plane; the front pair are seen in Fig. III at 15, 16, they are supported by projecting brackets fastened to the bottom piece of the log box, and are 110 grooved in their edges to receive an endless chain or belt passing around the whole four; to each of these pulleys is fixed at the center a vertical screw 25 which passes up from the bracket over the pulley to a corresponding bracket above, in which is a screw thread in which the screw works these last mentioned upper brackets (the front pair seen at 17, 18) support the movable or false bottom above described. 115

In front of the log box and midway between the pulleys 15, 16, and in line with them is a horizontal pulley supported by brackets and having above it the ratchet wheel 19, having the same axis. A pawl, 120 130

20, fixed upon an upright spindle, 21, adjustable upon it by screw, 22, at its loose end catches into the teeth of the ratchet wheel, to which it is kept close, when required by the spring 23, fastened to bracket 24, which by an elbow sustains also the upper part of spindle 21. The endless chain or belt is wound once around the pulley to which the ratchet wheel is attached, so that 5 when this pulley is turned the chain or belt passing around the other pulleys will cause them to turn and also the feed screws, 25, attached to them, which will cause the movable bottom of the log box and log when 10 attached to be lifted or lowered according to the direction in which they are turned. To turn the feed off as soon as it has raised the log sufficiently for each stroke of the knife, a cam is placed upon the upper 15 bracket which sustains the middle pulley, which cam is adjustable by a slot and screw passing through it into the bracket; and the end of the pawl is notched out so as to leave a projecting point on its under side 20 to catch in the ratchet wheel just long enough to give the necessary feed, when the upper or shorter part meets the projecting cam, and the pawl is instantly turned off the ratchet and the feed ceases 25 until it is renewed by the next return stroke.

In operating the machine, the process is as follows: The log is squared and the caul (6) is screwed to the under surface of the log, and the log and caul are placed in the 30 log-box through the open space in front of the box, and the clamp (7) is screwed up so as to hold the caul fast between the clamp pieces 5, 7. For cutting hard or dry woods the log should first be thoroughly steamed 35 in a close chest filled with hot water and steam together, so as to soften without burning the wood. The knife plate and edge are adjusted to the desired pitch by screws f , f , and the screws on the under side of the 40 knife plate. The pawl and its releasing cam are adjusted to feed the log to the thickness of the veneer required. The log-box is placed parallel with cross-head C, as shown by G, G, G, G. The cams N and P are 45 then in the position indicated by those letters respectively, the toes L'', L''', are in the positions indicated by the positions of those letters respectively; the knife edge e , e , is just approaching the log ready to begin the 50 stroke. Power being communicated to shaft D', in the direction of the arrows, the edge of the knife is at once brought into contact with the log by a drawing cut from right to left; at the same time cam N, presses 55 upon the toe L''', which being connected by arm K', and bar M, with the end of the log box at bracket g, forces the log box

back, as shown by the dark dotted lines, and brings the log against the knife at a varying angle, and so that the knife in 60 passing covers the whole upper surface of that end of log which is toward g. When the cam N, has passed the toe L''', the other end of the log box at g' by means of the connecting bar M', and arm Q, has brought 65 the toe L'', forward so that it meets the cam P, and being pressed upon by cam P, it vibrates the log box back by the same connections so that the surface of the log toward g', is covered by the knife at a varying 70 angle of the cut; this again brings N, and L''', into position to again vibrate the log box and the log to receive the stroke of the knife as before. The different positions of the log box and its connections are shown 75 by the black and red dotted lines, Fig. I. At each vibration of the box the ratchet wheel is brought against the point of the pawl and is turned the required distance 80 carrying with it the pulleys, the endless chain or belt and the feed screws, so as to keep up the feed.

The knife plate instead of being placed within the periphery of disk D, and under a mouth or slot as above described, may be 85 placed upon the extreme edge of the disk but eccentrically to the disk as above; in which case the diameter of the disk will be less. In cutting very hard or crutch woods 90 this mode of setting the knife may be 95 advantageous.

Having thus described my machine and the manner of operating the same, what I claim therein as my invention, and which I desire to secure by Letters Patent, is— 100

1. The revolving disk and knife placed eccentrically to the disk upon the under surface or upon the edge of the disk, and having a curved edge for cutting the log in the line or direction of the edge of the knife. 105

2. The vibrating of the log by means of the log box, arms, cams and toes connected with the rotation of the shaft of the disk as described, so as to present the whole top surface of the log to the edge of the knife 110 as it passes, and by a continuously varying line of cut or stroke.

3. I claim the manner of constructing the log box with the movable bottom composed of the caul and clamp pieces for holding, shifting and adjusting the log as above described. 115

4. I claim the combination of the log box and feed apparatus operating together as above described.

GILBERT BISHOP.
